ELECTROMAGNETIC RELAY

Fredric E. Wood, Oak Park, Ill., assignor to Associated Electric Laboratories, Inc., Chicago, Ill., a corporation of Delaware

Application June 15, 1939, Serial No. 279,315

1 Claim. (Cl. 175—336)

The present invention relates to electromagnetic devices and more particularly to electromagnetic relays of the switching type.

An electromagnetic relay conventionally comprises a field structure including a core provided with a winding, a movable armature carried by the field structure, and a set of switch springs operatively connected to the armature.

It is an object of the present invention to provide an improved relay of the type described, which is of rugged and economical construction and which is reliable and positive in operation.

Another object of the invention is to provide, in a relay of the type described, an improved arrangement for pivotally mounting the armature on the field structure and for locking the armature in place.

In brief, the objects set forth above are in part realized in accordance with one feature of the present invention by providing an electromagnetic relay comprising a longitudinally extending core, a substantially L-shaped field element including a first laterally and forwardly extending leg secured to one end of the core and a second longitudinally extending leg arranged in spaced-apart relation with respect to the core, and an armature. An arrangement including integral lugs provided on the outer end of the second leg of the field element and cooperating openings provided in the armature adjacent the inner end thereof is utilized for pivotally mounting the armature on the outer end of the second leg and in cooperating relationship with respect to the outer end of the core. Further, a substantially L-shaped bracket is provided which includes a first longitudinally extending arm secured to the second leg of the field element and a second laterally and rearwardly extending arm. A laterally and forwardly extending projection is carried by the second arm of the bracket which engages the ends of the lugs provided on the outer end of the second leg of the field element, thereby to lock the armature in place on the outer end of the second leg. Further the second arm of the bracket carries a spring which engages the armature in order to urge the armature in seated engagement with the outer end of the second leg of the field element, and a stop for limiting the pivotal movement of the armature away from the outer end of the core. Finally, the second arm carries a pair of switch springs, one of the switch springs being operatively connected to the armature.

The operative connection between the armature of the relay and the set of switch springs

carried thereby comprises a link formed of a suitable insulating material. The armature is connected to the link by an arrangement including an integral lug provided on the outer end of the armature and a cooperating opening provided in the link, the lug projecting through the cooperating opening and extending inwardly to provide an inwardly directed seat arranged to receive and engage the wall of the link adjacent the cooperating opening. Similarly, one of the switch springs of the set of switch springs is connected to the link by an arrangement including an integral lug provided on the outer end of the switch spring and a cooperating opening provided in the link, the lug projecting through the cooperating opening and carrying outwardly extending spaced-apart fingers to provide an outwardly directed seat arranged to receive and engage the wall of the link adjacent the cooperating opening. Finally the lugs respectively provided on the outer end of the armature and on the outer end of the switch spring and the respective cooperating openings provided in the link are so constructed and arranged that they are readily engageable and disengageable, thereby to facilitate ready placement and removal of the link.

Further features of the invention pertain to the particular construction and arrangement of the elements of the relay whereby the above-outlined and additional operating features are attained.

The novel features believed to be characteristic of the invention are set forth with particularity in the appended claim. The invention, both as to its organization and method of operation, together with further objects and advantages thereof, will best be understood by reference to the following specification taken in connection with the accompanying drawing, in which Figure 1 is a plan view of an electromagnetic relay constructed and arranged in accordance with the present invention; Fig. 2 is a longitudinal sectional view of the relay taken along the line 2—2 in Fig. 1; Fig. 3 is an end elevational view of the relay shown in Fig. 1; and Fig. 4 is a fragmentary exploded perspective view of the relay illustrating the mounting arrangement for the armature thereof.

Referring now more particularly to Figs. 1 to 3, inclusive, of the drawing, the electromagnetic relay there shown comprises a field structure including a longitudinally extending core 10 provided with a winding 11 and a substantially L-shaped field element 12 including a first laterally and forwardly extending leg 13 secured to one end of the core 10 by a screw 14, extending

through an opening provided in the leg 13 and threaded into a tapped hole provided in the end of the core 10, and a second longitudinally extending leg 15 arranged in spaced-apart relationship with respect to the core 10. The winding 11 surrounds the core 10 and is retained in place by a pair of spaced-apart retaining heads 16 and 17 arranged on the opposite ends of the winding 11 and surrounding the core 10, the retaining heads 16 and 17 being formed of a suitable insulating material.

Also the relay comprises a movable armature 18 and a substantially L-shaped bracket 19 including a first longitudinally extending arm 20 and a second laterally and rearwardly extending arm 21. As best shown in Figs. 2 and 4 of the drawing, the inner end of the armature 18 is pivotally mounted on the outer end of the leg 15 and the arm 20 is secured to the leg 15 by two screws 22 extending through openings provided in the arm 20 and threaded into tapped holes provided in the leg 15. The arrangement for pivotally mounting the inner end of the armature 18 on the outer end of the leg 15 comprises interfitting lugs respectively carried on the outer end of the leg 15 and on the inner end of the armature 18. Specifically, the intermediate portion of the outer end of the leg 15 is cut out to provide two lugs 23 spaced apart by an intervening notch 24; while the opposite sides of the armature 18 adjacent the inner end thereof are cut out to provide two spaced-apart lugs 25 and associated spaced-apart notches 26. Also the intermediate portion of the inner end of the armature 18 is cut out to provide a notch 27 disposed intermediate the two spaced-apart lugs 25. When the field element 12, the armature 18 and the bracket 19 are in assembled relationship the two spaced-apart lugs 23 provided on the leg 15 extend into and project through the two spaced-apart notches 26 provided in the armature 18; and the intermediate portion of the armature 18 is disposed in the notch 24 provided in the leg 15. Furthermore, the notch 27 provided in the armature 18 receives the leg 20.

The order to lock the inner end of the armature 18 in place on the outer end of the leg 15, an arrangement is provided which comprises two spaced-apart laterally and forwardly extending projections 28 carried by the arm 21 of the bracket 19. More particularly, the two spaced-apart projections 28 carried by the arm 21 of the bracket 19 overlie and directly engage the ends of the two spaced-apart lugs 23 carried by the leg 15 of the field element 12. This arrangement positively locks the inner end of the armature 18 in place on the outer end of the leg 15; yet, it provides for ready removal of the armature 18. This may be accomplished merely by unthreading the screws 22 from the tapped holes provided in the leg 15 and then removing the bracket 19, whereupon the inner end of the armature 18 may be removed from the outer end of the leg 15 in an obvious manner.

In addition to providing an arrangement for locking the inner end of the armature 18 on the outer end of the leg 15, the arm 21 of the bracket 19 carries a leaf spring 30, a stop 31, a set of switch springs 32 and a clamping plate 33 in stacked relationship. Specifically, the leaf spring 30 is arranged directly upon the arm 21, the stop 31 is arranged upon the leaf spring 30, and the switch springs of the set of switch springs 32 are separated from each other and from the stop 31 and the clamping plate 33 by

intervening strips 34 of a suitable insulating material. Finally the clamping plate 33, the switch springs of the set of switch springs 32, the strips 34 of insulating material, the stop 31, and the leaf spring 30 are retained in assembled and stacked relationship by two screws 35 extending through aligned openings provided therein and threaded into tapped holes provided in the arm 21. The set of switch springs 32 is illustrated as comprising two switch springs 36 and 37, although it will be understood that the set of switch springs 32 may comprise any reasonable number of switch springs. Furthermore, it is noted that the arm 21 of the bracket 19 has two sets of spaced-apart openings 21a and 21b provided therein which are disposed on opposite sides of the set of switch springs 32, these two sets of openings being arranged to fasten two additional sets of switch springs to the arm 21 or to fasten the arm 21 on a suitable support, as desired. When the two sets of openings 21a and 21b provided in the arm 21 of the bracket 19 are utilized to fasten the arm 21 to a support, the entire weight of the relay is supported by the arm 21. The switch springs 36 and 37 are respectively provided with terminals 36a and 37a to which electrical connections may be extended, and carry cooperating contacts adjacent the outer ends thereof, which are arranged in switching relationship and preferably formed of a suitable precious metal.

The leaf spring 30 is provided with an outwardly projecting and inwardly curved end 30a arranged in direct engagement with the inner end of the armature 18, thereby to urge the inner end of the armature 18 into seated engagement with the outer end of the leg 15 and to prevent longitudinal movement therebetween incident to the pivotal movement of the armature 18 away from the cooperating outer end of the core 10. Also the stop 31 is provided with an outwardly projecting and inwardly directed end 31a which cooperates with the armature 18 to limit the pivotal movement of the armature 18 away from the outer end of the core 10. Furthermore, the armature 18 has an opening provided therein, into which a rivet 38 formed of nonmagnetic material is securely fastened, the rivet 38 being arranged to engage the outer end of the core 10 when the armature 18 is moved toward the core 10. The arrangement of the rivet 38 carried by the armature 18 with respect to the outer end of the core 10 prevents the armature 18 from sticking to the outer end of the core 10 when the armature 18 is moved toward the outer end of the core incident to the energization of the winding 11.

In order operatively to connect the armature 18 and the movable switch spring 36 of the set of switch springs 32, an arrangement is provided which comprises a link 39 formed of a suitable insulating material. More particularly, the link 39 has a pair of spaced-apart openings 40 formed therein adjacent the inner end thereof and a centrally disposed opening 41 formed therein adjacent the outer end thereof, the opening 41 being arranged intermediate and in spaced-apart relationship with respect to the two openings 40. Two integral lugs 42 are provided on the outer end of the armature 18, these lugs being arranged to project through the cooperating openings 40 provided in the link 39. Similarly, an integral lug 43 is provided on the outer end of the switch spring 36, this lug being arranged to project through the cooperating opening 41 pro-

vided in the link 39. More specifically, each of the lugs 42 provided on the outer end of the armature 18 is curved inwardly to provide an inwardly directed seat arranged to receive and engage the wall of the link 39 adjacent the cooperating opening provided therein; while the lug 43 provided on the outer end of the switch spring 36 carries integral and outwardly extending spaced-apart fingers 44 which provide an outwardly directed seat arranged to receive and engage the wall of the link 39 adjacent the opening provided therein.

The lugs 42 provided on the outer end of the armature 18, the lug 43 provided on the outer end of the switch spring 36, and the cooperating openings 40 and 41 provided in the link 39 are so constructed and arranged that they are readily engageable and disengageable, thereby to facilitate ready placement and removal of the link 39. More particularly, the link 39 may be readily removed by forcing the switch spring 36 inwardly, thereby to disengage the outwardly directed seat provided in the lug 43 and the associated wall of the link 39 adjacent the cooperating opening 41, and then by swinging the link 39 away from the switch spring 36. The inwardly directed seats provided in the lugs 42 and the associated walls of the link 39 adjacent the cooperating openings 40 may then be disengaged, in an obvious manner, in order to permit the link 39 to be completely removed from the assembly.

Furthermore, it is noted that two spaced-apart slots 45 are provided on the opposite sides of the link 39 adjacent the outer end thereof, these slots being arranged to accommodate the two cooperating lugs provided on the two switch springs of the two sets of switch springs, in the event the relay comprises three sets of switch springs, as previously noted. More particularly, the two sets of switch springs, which may be secured to the arm 21 of the bracket 19 by utilizing the two sets of aligned openings 21a and 21b formed in the arm 21, may be operatively connected to the link 39 by utilizing the slots 45 provided therein, in the manner previously explained.

In assembling the relay, the leg 13 of the field element 12 is first secured to the core 10 with the screw 14, and the winding 11 is then placed upon the core 10. Subsequently, the inner end of the armature 18 is positioned on the outer end of the leg 15 of the field element 12, and the bracket 19 is secured in place, thereby to lock the inner end of the armature 18 upon the outer end of the leg 15. Thereafter, the leaf spring 30, the stop 31, the set of switch springs 32, the insulating strips 34 and the clamping plate 33 are assembled upon the arm 21 of the bracket 19 in an obvious manner, the engagement between the outer end 30a of the leaf spring 30 and the inner end of the armature 18 retaining the inner end of the armature 18 in seated engagement with the outer end of the leg 15. Finally, the armature 18 is operatively connected to the switch spring 36 by placing the link 39 in its cooperating position with respect to the lugs 42 and 43 respectively provided on the outer ends of the armature 18 and the switch spring 36.

Normally the switch spring 36 exerts a force 70 through the link 39 upon the outer end of the armature 18, thereby to restrain the armature 18 away from the outer end of the core 10 and toward the outer end 31a of the stop 31. When

the winding 11 is energized, the magnetic flux traversing the core 10, the field element 12 and the armature 18 causes the armature 18 to be moved toward the outer end of the core 10, the inner end of the armature 18 being pivoted in a clockwise direction, as viewed in Fig. 2, about the outer end of the leg 15 of the field element 12. This movement of the armature 18 toward the outer end of the core 10 is transmitted by the link 39 to the switch spring 36, in order to cause the contacts carried by the switch springs 36 and 37 to be moved into engagement. When the winding 11 is deenergized the switch spring 36 then moves the armature 18 away from the outer end of the core 10, the inner end of the armature 18 being pivoted in a counterclockwise direction, as viewed in Fig. 2, about the outer end of the leg 15 of the field element 12. When the switch spring 36 returns to its normal position the set of contacts carried by the switch springs 36 and 37 are moved into disengagement. Accordingly, the movement of the armature 18 is controlled jointly by the energization of the winding 11 and the resiliency of the switch spring 36; and the armature is prevented from sticking to the outer end of the core 10 due to any residual magnetism in the core 10 by the rivet 38 formed of non-magnetic material.

In view of the foregoing it is apparent that an improved electromagnetic switching relay is provided which is of rugged and economical construction and which is reliable and positive in operation.

While there has been described what is at present considered to be the preferred embodiment of the invention, it will be understood that various modifications may be made therein, and it is intended to cover in the appended claim all such modifications as fall within the true spirit and scope of the invention.

What is claimed is:

An electromagnetic relay comprising a longitudinally extending core, a substantially L-shaped field element including a first laterally and forwardly extending leg secured to one end of said core and a second longitudinally extending leg arranged in spaced-apart relationship with respect to said core, an armature, means including integral lugs provided on the outer end of said second leg and cooperating openings provided in said armature adjacent the inner end thereof for pivotally mounting the inner end of said armature on the outer end of said second leg and in cooperating relationship with respect to the outer end of said core, a substantially L-shaped bracket including a first longitudinally extending arm removably secured to said second leg and a second laterally and rearwardly extending arm, means including a laterally and forwardly extending projection carried by said second arm and engaging the ends of said lugs for locking the inner end of said armature in place on the outer end of said second leg, means including a leaf spring carried by said second arm and projecting forwardly into engagement with said armature for urging the inner end of said armature in seated engagement with the outer end of said second leg, and means including a stop carried by said second arm and projecting forwardly over said armature for limiting the pivotal movement of said armature away from the outer end of said core.

FREDERIC E. WOOD.
